UNITED STATES PATENT OFFICE.

RAMON GARCIA MOYA, OF CORNELLA DE LLLOBREGAT, SPAIN.

SHUTTLELESS LOOM.

Application filed October 22, 1927, Serial No. 227,995, and in Spain October 27, 1926.

This invention relates to looms without shuttles of the type in which the weft is taken from a bobbin fixed to one side of the loom and in which for inserting the weft into the shed use is made of a flexible arm or needle formed by a strip of steel secured to the end of an oscillating arm disposed on one side of the loom, the movement of oscillation of which arm causes the said strip to be inserted into the shed so as to pass the weft as far as the other side of the cloth which is being woven and then withdrawn from the shed and curved along approximately the circular path traced out by the end of the arm to which it is secured.

The improvements forming the subject of the present invention relate more particularly to the arrangement of the slay and the mode of actuating the latter for facilitating the insertion of the weft carrying stick into the shed, and also to the mode of actuating the arm at the end of which is secured the weft carrying stick.

In a loom according to the invention the slay is greatly simplified and is simply formed by the reed and the uprights or rods necessary to support the latter so that it can make a movement of oscillation, and this movement of oscillation, instead of being transmitted by means of a crank shaft as in the usual looms, is transmitted by means of an eccentric of form such that during the greater part of the rotation of the eccentric the slay remains held in the withdrawn position towards the rear and only for a small part of the rotation of the eccentric the slay makes a rapid movement of advance in order to close up the weft and of recoil in order to return and remain fixed in the rear position. The result is thus obtained that the shed remains free for the passage of the weft carrying stick for the greatest possible length of time and, at the same time, that the angle of oscillation of the slay may be very small because after having closed the weft it simply has to move back through the angle necessary to permit the weft carrying stick to pass through the shed.

The arm or lever which actuates the weft carrying stick receives its movement, according to the invention, by means of a crank and connecting rod mechanism driven by the main shaft of the loom, and this mechanism gives a reciprocating oscillatory movement to a toothed sector engaging with a pinion of

small diameter mounted upon the pivot of the arm upon which is mounted the weft carrying stick.

It is thus possible, with a small throw of the crank and a small oscillation of the toothed sector, to give the arm upon which is mounted the weft carrying stick an oscillation through as much as 180° or even more and in this way the space occupied by the weft carrying stick when it is curved into the form of a circular arc is made very small relatively.

The accompanying drawings illustrate a loom of the type specified provided with the improvements forming the subject of the present invention.

Fig. 1 is a front view of the loom.

Fig. 2 is a plan view of the same.

Fig. 3 is a side view and

Fig. 4 a section taken along the line IV—IV in Fig. 1, certain parts of the machine being omitted for clearness.

As shown in the drawings, the loom comprises a frame 1 at the back of which is mounted in the usual manner a warp beam 2 upon which is disposed the warp and at the front part another beam 3 upon which is wound the cloth manufactured. This frame 1 carries the main shaft 4 of the loom which is driven by the driving pulleys 27 and which replaces the usual crank shaft of looms. This main shaft 4 transmits movement through the medium of a transmission chain 5 to a lower shaft 6 which is the tappet shaft and carries the tappets for actuating the healds 7 in the usual manner.

The weft comes from a fixed bobbin 8 and is inserted into the shed by means of a weft inserting stick or needle formed by a steel strip 9 which is secured to the end of an oscillating arm 11 and, by the movement of oscillation of this arm, it is inserted into the shed and withdrawn from the latter. This stick 9 terminates at its end in a head through which passes the weft thread so that when it is inserted into the shed it inserts the weft thread double and at the left hand end of the loom is provided a mechanism 10, which is not shown in detail in the drawings, which catches the bend or knot formed by the end of the inserted double weft thread and ties it forming the selvedge of the piece of cloth.

According to the present invention the slay, which is reduced to two posts 12 which carry at their upper part the reed 13, is dis-

posed in such a way that it makes a very small angle of oscillation and that during the greater part of the rotation of the main shaft 4 it remains withdrawn in the position shown 5 in Fig. 4 in order to permit the weft carrying stick 9 to pass easily and then when this weft carrying stick has been inserted in the shed and has turned to return, the slay makes a rapid forward movement in order to close 10 up the weft and a rapid return movement to remain once more held in the furthest back position shown in Fig. 4. For this purpose each of the posts 12 of the slay comprises at 15 its back part a projection or lug 14 provided with a pin or roller 15 which enters the groove of an eccentric 16 mounted upon the main shaft 4. As shown in detail in Fig. 4, this eccentric 16 is circular over the greater 20 portion of its periphery and for a small angle only comprises the eccentric portion intended to give the slay 12 the rapid forward and return movement.

In this way it is possible to reduce the oscillation of the slay and in return dispose of 25 the greater part of the time occupied in the rotation of the main shaft 4 for making the weft carrying stick pass through the shed. By virtue of this arrangement the loom may 30 be made to work at a relatively high speed without the movement of the slay impeding the movement of the weft carrying stick.

The reciprocating movement of the weft carrying stick 9 is produced by the movement of oscillation of an arm 11 to the end 35 of which is secured the strip or stick 9 but according to the present invention the mechanism employed for transmitting the movement of oscillation to this arm 11 is disposed in such a way that this movement can have a 40 great amplitude, reaching easily 180° and even exceeding this angle, with the result that the radius of the circular arc necessary for taking up the whole length of the weft carrying stick 9 is very small and consequently 45 that the loom occupies less space.

For this purpose the arm 11 to the end of 50 which is secured the weft carrying stick is mounted upon a shaft 17 which carries a toothed pinion 18 which is rotated by means of a toothed sector 19 mounted upon the lower shaft 20. This shaft 20 receives a

movement of oscillation through the medium of a lever 21 secured to the shaft 20 and a connecting rod 22 pivotally connected to the pin 23 on the flywheel 24 of the loom mounted upon the main shaft 4. In this way a relatively small oscillation of the arm 21 and of the shaft 20 may be made to give the shaft 17 and the arm 11 a very large angle of oscillation, the ratio depending solely upon the ratio between the radius of the pinion 18 and that of the sector 19. In the contrary case, this large angle of oscillation of the arm 11 could not be obtained because the oscillation of the rod crank 21 which is driven directly 60 by the rod 22 has always to take place through a small angle for it to be possible to transmit the movement from the crank 23 of the shaft 4.

In order to make the stick 9 curve over a 70 circular arc when it is bent by the movement of the arm 11, there is provided on the loom frame a member 25 of semi-circular form provided with the necessary number of rollers 26 for guiding the stick 9 both when it 75 is curved by the movement of the arm 11 and when it leaves this member 25 and is inserted in the shed.

I claim:—

1. A shuttleless loom including a weft inserting mechanism comprising a flexible weft carrying rod, an arm secured to said rod, mechanism for oscillating said arm, and guiding means for said rod, said means comprising an arcuate member and a plurality of rollers mounted thereon, said rod being constrained to conform substantially to said member when withdrawn.

2. A loom as claimed in claim 1, said oscillating mechanism comprising a pinion secured to said arm, a tooth segment meshing with said pinion, said segment having a larger radius than said pinion, a rocker arm secured to said segment, a crank shaft, and a connecting link between said crank shaft and said rocker arm whereby an oscillation of small amplitude of said rocker arm causes a relatively great oscillation of said first mentioned arm.

In testimony whereof I have signed my 100 name to this specification.

RAMON GARCIA MOYA.
